UNITED STATES PATENT OFFICE.

EDWIN B. STIMPSON, OF BROOKLYN, NEW YORK.

LEGGIN.

SPECIFICATION forming part of Letters Patent No. 271,150, dated January 23, 1883.

Application filed October 27, 1882. (No model.)

To all whom it may concern:

Be it known that I, EDWIN B. STIMPSON, a citizen of the United States, residing at Brooklyn, in the county of Kings and State of New York, have invented a new and useful Improvement in Leggins, of which the following is a specification.

My invention relates to improvements in leggins or "spatterdashes," such as described and claimed in the specification of Letters Patent granted to William G. Rule, dated January 15, 1867, and numbered 61,265.

My invention consists in a novel construction of the elastic metal frame and novel mode of inserting the same within the leggins or spatterdashes, whereby the manufacture of the leggins is much simplified, as will be fully understood by reference to the accompanying specification and the drawings annexed, which form part of the same.

Referring to the drawings, Figure 1 is a perspective view of my improved leggin or spatterdash complete ready for use. Fig. 2 is an internal view of the covering of a similar leggin unfinished and spread open, with parts broken away in order to illustrate the mode of inserting the frame within it, and also showing one side of the side braces and portions of the spring, ankle, and knee-bands in position for insertion. Fig. 3 is a vertical section on the line $x-x$, Fig. 2. Fig. 4 is a perspective view of the framing separately. Fig. 5 is a perspective view of one of the side braces. Fig. 6 is a perspective view of portions of the elastic frame, illustrating a slight variation from the construction shown in the other figures.

In each of the views similar letters of reference are employed to indicate corresponding parts wherever they occur.

A represents the covering or body of the leggin or spatterdash, which may be formed of leather or any other suitable material, and of any desired or suitable size, pattern, or shape.

B represents the spring ankle-band, and B' the spring knee-band, each of which, according to my invention, consists of a coiled spring having a loop at each end. In the example represented each is formed of a strip of thin steel doubled or folded upon itself in such man-

ner that the two halves shall lie closely together and leave a loop, b, at one end for the passage and retention of the side brace D, while at the opposite end of it a loop, b', is formed for the passage and retention of the side brace D'. The loop b is formed by the return or folded end b² of the spring, while the loop b' is formed by turning back a small portion of the outer layer of the spring and riveting the same to the inner layer, as shown at b³. The side braces, D and D', are formed of straight strips of band-steel, the upper ends, d, of which are bent over at d', so as to form hooks d², adapted to hook respectively over the loops b and b' of the side braces, D and D', as shown by dotted lines in Fig. 4. At their lower ends, d⁴, the side braces, D and D', are formed straight and flat, and are adapted to be passed through the loops b and b', respectively, of the spring ankle-band B. Holes or perforations d⁵ d⁵ are formed in the ends d⁴ of the braces D and D', as shown in Fig. 4, by means of which the said braces may be stitched to the cover or body A, as hereinafter explained.

The cover or body A, on its inside, as shown by Fig. 2, is formed with horizontal pockets a a', adapted for the reception of the ankle and knee bands B and B', respectively. The pockets a a' are formed respectively by stitching lining-pieces, of leather or other material, A' A, to the inner side of the cover or body A. The pockets a and a' terminate at the opposite sides of the body A in vertical pockets a² a³, adapted for the reception respectively of the side braces, D and D'. These pockets are formed, in a similar manner to the pockets a, by stitching pieces of material a⁴ a⁵ to the inner side of the body A.

In constructing a leggin or spatterdash according to my invention the pockets a a' and a² and a³ are completed, as shown by Fig. 2, before their respective metallic parts are inserted, access to the pockets a and a' being obtained through the pocket a³, which is left open or unstitched, as shown at Fig. 2, where a portion of the knee-band B' is shown in position for insertion into the pocket a', while the similar portion of the ankle-band B is shown with its end just inserted within the pocket a. I first insert the bands B and B' into and through the pockets a and a', so that their loops b and b' shall enter the pocket a², while the

loops b are in position to correspond with the pocket a^3 when closed. I then pass the end d^4 of the outer side brace, D' , through the slit a^6 into the pocket a^2 . I then pass the said end through the loop b' in the knee-band B' , and also through the loop b' of the ankle-band B . I then force the said brace D' fully home into the pocket a^2 , and as far as permitted by the hook d' , which comes to a bearing on the top of the knee-band. I then secure the said brace in position by stitching it through the holes d^5 d^6 , and through the covering A' and lining-piece A^2 . The parts B B' and D having been placed in position, I now pass the end d^4 of the side brace D' through the loops b of the bands B B' and place the same in proper position, as shown by Fig. 2, after which I close up the open side and ends of the pocket a^3 by stitching, after which I stitch the brace D in position through its holes d^5 d^6 in a similar manner to that described in reference to the brace D' . The article is now complete.

The side braces, instead of having their lower ends made to project downward below the loops b' b^2 of the ankle-band, may have their lower ends made with hooks d^6 , as shown in Fig. 6, like their upper ends, and these hooks may be hooked into the loops b' b^2 of the ankle-band after the bands and braces have been separately inserted into their respective pockets a a' a^2 a^3 ; all that is then necessary to enable this to be done is to draw up or contract the lower

parts of the covering and pockets sufficiently to enable the loops of the ankle-band, which is already in the pocket a , to be passed over the ends of the hooks d^6 , and then to pull down or extend the covering, to let the loop down into the hook d^6 . The side pockets, a^2 a^3 , being then sewed up at the bottom, the side braces are confined in place without sewing through them.

Having thus described my invention, what I claim, and desire to secure by Letters Patent, is—

1. The combination, in an elastic leggin or spatterdash frame, of two elastic bands formed with loops at their opposite ends, and two side braces formed with hooks at their upper ends to hook into the loops of the upper band, and passing through the loops of both bands, substantially as and for the purpose described.

2. The combination, with the covering A , provided with pockets a a' a^2 a^3 , of the double coiled spring-bands B B' , having looped ends, and the hooked side braces, D D' , the said bands and braces being inserted into the said pockets, and being hooked into the loops of said double coiled spring, all substantially as herein described.

EDWIN B. STIMPSON.
